ROTARY TYPOGRAPHIC PRINTING PRESS

Howard M. Barber, Pawcatuck, Conn., assignor to
 C. B. Cottrell & Sons Company, Westerly, R. I.,
 a corporation of Delaware

Application November 14, 1940, Serial No. 365,623

10 Claims. (Cl. 101—178)

In printing all-over designs by typographic presses it has heretofore been necessary to use an engraved form cylinder as there was no suitable available space on the cylinder for both the plates and their necessary clamping devices.

The object of this invention is to provide means whereby all-over designs may be printed typographically with ample space provided for the plates and their plate clamping devices.

This invention includes printing presses arranged to print in one or more colors, each color printing unit comprising a pair of plate cylinders provided with duplicate plates clamped thereon and so arranged with respect to one another on the two plate cylinders that an all-over design may be printed by the coaction of the two plate cylinders.

This invention further comprises a single inking mechanism for both of the cylinders arranged to print a selected color, means being provided for supplying ink alternately to the two plate cylinders in the required quantity.

In the accompanying drawings:

Fig. 1 represents in diagram a side elevation of a five color rotary typographic printing press embodying my invention;

Fig. 2 represents a detail side elevation showing the interconnected drive for the several elements;

Fig. 3 represents a detail side elevation showing the means for operating the ink fountain roll and the ductor roller, and the means for operating one of the ink distributor rollers;

Fig. 4 represents a detail section of the same;

Fig. 5 represents a side view of one of the plate cylinders with a staggered overlapping arrangement of the plates thereon;

Fig. 6 represents a cross section taken in the plane of the line VI—VI of Fig. 5, looking in the direction of the arrows;

Fig. 7 represents a cross section taken in the plane of the line VII—VII of Fig. 5, looking in the direction of the arrows; and

Fig. 8 represents a development in plan of the plate arrangement.

The five color rotary typographic printing press herein illustrated is shown as comprising an impression cylinder, five pairs of plate cylinders coacting therewith and a single inking mechanism for each pair of plate cylinders. Each plate cylinder of a pair is arranged to carry one-half of the plates for a selected color, said plates being spaced apart in staggered arrangement to permit the locking of the plates on their cylinder in the

required positions with respect to the duplicate plates on its companion cylinder.

If desired, a drying unit may be provided, which drying unit in the present instance is shown as located in position to dry the ink after three color impressions have been made on the web.

The impression cylinder is denoted by 1, the traveling web by 2 and the drying unit by 3.

As the five printing units are the same except for the color to be printed, the construction, arrangement and operation of one only of these printing units will be specifically described herein.

One plate cylinder of the coacting pair of cylinders is denoted by 4, its plate inking rollers by 5, their ink cylinder by 6 and its distributor roller by 7. The other plate cylinder of the pair is denoted by 8, its plate inking rollers by 9, their ink cylinder by 10 and its distributor by 11.

The ink fountain is denoted by 12, its fountain roll by 13, the ductor roller by 14, the ink feed roller by 15, the transfer roller by 16 and the ink drum by 17. This ink drum 17 is intermittently contacted by the distributor roller 7 to feed the ink to the plate cylinder 4 and it is at all times contacted by the distributor roller 11 to feed the ink to the plate cylinder 8.

The fountain roll 13 and the ductor roller 14 may be operated from the rotary cam shaft 18 as follows: a crank disc 19 on the cam shaft 18 is operatively connected by a rod 20 to one arm 21 of a rock lever pivoted on the shaft 22 of the fountain roll 13; the other arm 23 of which rock lever carries a pawl 24 engaged with a ratchet wheel 25 fast on the said fountain roll shaft 22.

This rotary cam shaft 18 is provided with a cam 26 which is engaged by a stud or roller 27 on the free end of one arm 28 of a rock lever carried by a shaft 30, the other arm 31 of which rock lever carries the ductor roller 14. A second rotary cam shaft 32 carries a cam 33 which is engaged by a stud or roller 34 on the free end of one arm 35 of a rock lever pivoted on the shaft 36 of the ink cylinder 6; the other arm 37 of which lever carries the distributor roller 7. This cam 33 therefore moves the distributor roller 7 into and out of contact with ink drum 17 at the proper intervals.

The driving connection between the several operating elements is herein shown as follows: the impression cylinder gear 38 is a wide faced gear and not only meshes with the two plate cylinder gears 39, 40 but also meshes with the gear 41 loosely mounted on the plate cylinder shaft 40*, which gear 41 meshes with an intermediate gear 41*. This gear 41* meshes with two ink cylinder gears 42, 43 and also with the ink drum gear 44.

This ink drum gear 44 meshes with an intermediate gear 45 which in turn meshes with the ink feed roller gear 46. This ink drum gear 44 also meshes with an intermediate gear 47 which in turn meshes with a gear 48 on the cam shaft 18 which controls the operation of the fountain roll and the ductor roller. This cam shaft 18 is also provided with a small gear 49 which meshes with a large gear 50 carried by the cam shaft 32 which controls the operation of the distributor roller 7.

The speed relation between these two cam shafts 18 and 32 is such that the cam shaft 18 rotates at twice the speed of the cam shaft 32. The distributor roller 7 is therefore moved into contact with the ink drum 17 to feed the ink to the plate cylinder 4, every other ink application of the ductor roller 14 to the ink feed roller 15; thereby causing the ink supplied from the ink fountain 12 to be alternately fed to the plate cylinders 4 and 8. The supply of ink is controlled by the distance the fountain roll travels for each throw of the ductor roller. The supplies are fed alternately to the plate cylinder 4 through the distributor roller 7 and then to the plate cylinder 8 through the distributor roller 11.

As the two plate cylinders 4 and 8 which coact to print an all-over design in a selected color are duplicates, one only of these plate cylinders has been shown in detail. The plates which are arranged in staggered order around and along the plate cylinder, are denoted by 51 and the spaces between the plates are denoted by 52. It will be seen that these spaces provide ample room for the usual plate clamping devices, not shown herein. It will also be seen that the plates overlap so that the printing surfaces of the plates on one cylinder are of sufficient area to be complemented by the plates on the companion cylinder, whereby an uninterrupted all-over design may be printed by the coaction of the plates on the two plate cylinders.

It will also be seen that the same fountain setting can be used for both plate cylinders as the plates on one cylinder are duplicates of the plates on the other cylinder.

It will also be seen that by placing half of the plates on each plate cylinder an uninterrupted all-over design in typographic printing may be obtained because, as heretofore stated, there is ample space left on both plate cylinders to permit the use of the usual plate clamping devices.

It is obvious that to obtain the desired all-over design printing the two plate cylinders must be arranged and adjusted to bring the plates on the second plate cylinder into position to print in the spaces left by the staggered relationship of the plates on the first printing cylinder.

It is also obvious that in multicolor printing the several pairs of plate cylinders must be timed with respect to one another so as to print in proper register the all-over design in colors.

It is evident that various changes may be resorted to in the construction, form and arrangement of the several parts without departing from the spirit and scope of my invention, and hence I do not intend to be limited to the particular embodiment herein shown and described, but what I claim is:

1. In a multicolor rotary typographic printing press, a single impression cylinder, a plurality of pairs of plate cylinders coacting with said impression cylinder to print an all-over design in selected colors, and an inking mechanism for each pair of plate cylinders, the plate cylinders

of each pair being provided with duplicate plates.

2. In a rotary typographic printing press, a single impression cylinder, a pair of plate cylinders coacting with said impression cylinder to print an all-over design in a selected color, and an inking mechanism for said plate cylinders, the plate cylinders being provided with duplicate plates arranged in staggered order.

3. In a multicolor rotary typographic printing press, a single impression cylinder, a plurality of pairs of plate cylinders coacting with said impression cylinder to print an all-over design in selected colors, and an inking mechanism for each pair of plate cylinders, the plate cylinders of each pair being provided with duplicate plates arranged in staggered order.

4. In a multicolor rotary typographic printing press, a single impression cylinder, a plurality of pairs of plate cylinders coacting with said impression cylinder to print an all-over design in selected colors, and an inking mechanism for each pair of plate cylinders, and means for supplying ink alternately to the plate cylinders of each pair.

5. In a rotary typographic printing press, a single impression cylinder, a pair of plate cylinders coacting with said impression cylinder to print an all-over design in a selected color, an inking mechanism for said plate cylinders, and means for supplying ink alternately to the plate cylinders, said means including a ductor roller, a distributor roller and coacting elements for operating them at the proper intervals.

6. In a multicolor rotary typographic printing press, a single impression cylinder, a plurality of pairs of plate cylinders coacting with said impression cylinder to print an all-over design in selected colors, an inking mechanism for each pair of plate cylinders, and means for supplying ink alternately to the plate cylinders of each pair, said means including a ductor roller, a distributor roller and coacting elements for operating them at the proper intervals.

7. In a rotary typographic printing press, an impression cylinder, a pair of plate cylinders coacting to print an all-over design in a selected color, an inking mechanism for said plate cylinders, and means for supplying ink alternately to the plate cylinders, said means including a ductor roller, a distributor roller and coacting elements for operating the ductor roller twice for each operation of the distributor roller.

8. In a multicolor rotary typographic printing press, an impression cylinder, a plurality of pairs of plate cylinders coacting to print an all-over design in selected colors, an inking mechanism for each pair of plate cylinders, and means for supplying ink alternately to the plate cylinders of each pair, said means including a ductor roller, a distributor roller and coacting elements for operating the ductor roller twice for each operation of the distributor roller.

9. In a rotary typographic printing press, an impression cylinder, a pair of plate cylinders coacting to print an all-over design in a selected color, an inking mechanism for said plate cylinders, and means for supplying ink alternately to the plate cylinders, said means including a ductor roller, a fountain roll and a distributor roller, a rotary cam shaft for controlling the operation of the ductor roller and fountain roll and a second rotary cam shaft for controlling the operation of the distributor roller.

10. In a multicolor rotary typographic print-

ing press, an impression cylinder, a plurality of pairs of plate cylinders coacting to print an all-over design in selected colors, an inking mechanism for each pair of plate cylinders, and means for supplying ink alternately to the plate cylinders of each pair, said means including a ductor

5 roller, a fountain roll and a distributor roller, a rotary cam shaft for controlling the operation of the ductor roller and fountain roll and a second rotary cam shaft for controlling the operation of the distributor roller.

HOWARD M. BARBER.
